UNITED STATES PATENT OFFICE.

LOUIS KAPLAN, OF NEW YORK, N. Y.

RUBBER HEEL.

1,422,446.

Specification of Letters Patent. Patented July 11, 1922.

Application filed May 27, 1921. Serial No. 473,144.

To all whom it may concern:

Be it known that I, LOUIS KAPLAN, a citizen of the United States, residing at New York, in the county of New York and State of New York, have invented certain new and useful Improvements in Rubber Heels, of which the following is a specification, reference being had therein to the accompanying drawing.

10 The present invention relates to rubber or resilient heels, and more especially to detachable slip-on heels having marginal flanges or lips to fit on and embrace the heels; and it is an object of the invention to provide additional means for retaining the rubber heel firmly in place on the heel of the shoe or other article of foot wear.

Another object is to assemble an elastic band with the rubber heel in such a way as 20 to embrace the shoe heel and hold the rubber or cushion heel in place effectively.

A further object is the provision of a rubber or cushion heel of the character indicated which is simple and inexpensive in 25 construction, as well as convenient and practical in use.

With the foregoing and other objects in view, which will be understood as the description proceeds, the invention resides in 30 the construction and arrangement of parts, as hereinafter described and claimed, it being understood that changes can be made within the scope of what is claimed, without departing from the spirit of the invention.

35 The invention is illustrated in the accompanying drawing, wherein—

Figure 1 is a median vertical section of the detachable heel in position on the shoe heel.

40 Fig. 2 is a section on the line 2—2 of Fig. 1 showing the detachable heel and parts thereof as when in position on the shoe heel, said shoe heel being removed.

Fig. 3 is a perspective view showing a 45 modification.

Fig. 4 is a median vertical section of another variation taken on the line 4—4 of Fig. 5.

Fig. 5 is a plan view of the third form of 50 detachable heel.

The detachable heel 7, which is composed of rubber or other cushioning material, is provided with a marginal elastic flange or lip 8 which tapers upwardly, to be slipped 55 on and to embrace the heel 9 of a shoe, slipper or other article of foot wear, this type

of detachable heel being used especially on "French" heels of women's foot wear, to enable the heel 7 to be readily applied and removed for different occasions. The heel 7 when applied prevents the heel from slipping and also eliminates wear on the main heel, and the cushion heel can be removed when dancing, or whenever heel 7 would interfere with the wishes of the wearer. 65

Such detachable heels have been in extensive use, but are apt to become loosened or lost, owing to the imperfect grip of the flange or lip 8 on the heel 9, and, in carrying out the present invention, additional means 70 is provided for retaining the detachable heel on the main heel. As shown in Figs. 1 and 2, an elastic band 10 of suitable cross section and of rubber is vulcanized, cemented or otherwise secured to the rear portion of the 75 flange 8 on the inner side thereof, and is inclined, so as to embrace the heel 9 tightly with the forward portion of the band 10 disposed above the breast portion of the flange 8. The band 10 will therefore exert an upward and forward pull on the rear portion of the flange 8, to hold the heel 7 snugly up against the heel 9, and thereby resist the tendency for the heel 7 to become loosened or lost. 80

For purpose of ornamentation, the margin of the heel 7 can be provided with apertures or recesses 12.

In applying the detachable heel to the heel 9, the band 10 is easily stretched to 90 pass over the heel 9, in slipping the flange 8 on the heel 9, and the band 10 when released will assume the position as shown in Fig. 1.

In the modification shown in Fig. 3, the detachable cushion heel 7' has the retaining 95 flange or lip 8' and the marginal apertures 12' as in the form hereinbefore described, and the elastic retaining band 10', instead of being vulcanized, cemented or similarly secured to the flange 8', is threaded through 100 slots 11' provided in the rear portion of the flange 8', thereby attaching the lower rear portion of the elastic band with the rear portion of said flange, so that the band can embrace the shoe heel and hold the rear portion of the flange 8' snugly in place. 105

In the variation shown in Figs. 4 and 5, another manner of connecting the elastic band with the retaining flange of the detachable heel 7" is shown. Thus, the rear portion of the band 10", which is disposed above the flange 8", is connected with the rear por- 110

tion of the flange by an integral web 11", so that when the heel 7" is applied to the shoe heel and the band 10" stretched over the shoe heel to embrace same, the heel 7" is held 5 tightly in place. Figs. 4 and 5 also show the upper surface of the heel 7" as being provided with grooves 13" whereby to provide a friction surface to engage the tread of the heel of the shoe or other article of 10 foot wear, to eliminate possible slipping between the two heels and give cushioning action.

Having thus described the invention, what is claimed as new is:—

15 1. A detachable heel having a marginal retaining flange to embrace the heel of an article of foot wear, and an elastic band to

embrace the second named heel having one portion connected to the corresponding portion of said flange and its opposite portion 20 free to be disposed at the opposite portion of the second-named heel above said flange.

2. A detachable heel having a marginal retaining flange to embrace the heel of an article of foot wear, and an elastic band to 25 embrace the second named heel connected at its rear portion to the rear portion of said flange, the forward portion of said band being free to be disposed at the breast of the heel above said flange.

30 In testimony whereof I hereunto affix my signature.

LOUIS KAPLAN.
